UNITED STATES PATENT OFFICE.

EDWARD F. DONNELLY, OF MALDEN, MASSACHUSETTS, ASSIGNOR OF ONE-THIRD TO
ELBRIDGE G. KELLEY AND ONE-THIRD TO RALPH F. KELLEY, BOTH OF PEABODY,
MASSACHUSETTS.

ROOF-FLANGE.

1,278,120.

Specification of Letters Patent. Patented Sept. 10, 1918.

Application filed October 18, 1917. Serial No. 197,342.

To all whom it may concern:

Be it known that I, EDWARD F. DONNELLY, a citizen of the United States, residing at Malden, county of Middlesex, State of Massachusetts, have invented an Improvement in Roof-Flanges, of which the following description, in connection with the accompanying drawing, is a specification, like characters on the drawing representing like parts.

10 This invention relates to roof flanges and has for its object to provide a novel roof flange which is simple in its construction and inexpensive to manufacture; which can be used equally well on a flat roof, a roof 15 having a steep pitch, or a roof having any pitch between the two, and which has other advantages, all as will be more fully hereinafter set forth.

In order to give an understanding of my 20 invention I have illustrated in the drawings a selected embodiment thereof which will now be described, after which the novel features will be pointed out in the appended claim.

25 Figures 1, 2 and 3 are longitudinal vertical sections through a roof flange embodying my invention showing the flange applied to roofs of different pitch;

Fig. 4 is a top plan view of a roof flange 30 with a portion of the flashing broken out;

Fig. 5 is a section on the line 5—5, Fig. 4.

My improved roof flange is formed with a bottom 1 adapted to rest on the roof 2 and it has a wall or curb 3 rising from the 35 bottom 1 and forming a space to receive the usual packing 4. This wall or curb 3 has a general oval shape and the end portions 5 and 6 thereof are inclined in the same direction relative to the plane of the bottom 1.

40 The curb 3 thus forms an oval space having its axis inclined to the bottom 1. The wall or curb 3 is situated a slight distance from the peripheral edge 7 of the bottom 1 so that a peripheral flange 8 is presented exterior 45 to the wall 3. 9 is the usual copper flashing which encircles the wall 3 and rests on the flange 8, said flashing being preferably soldered to the flange 8, as shown at 10, thereby making an absolutely tight joint.

50 The bottom 1 of the roof flange is provided with an opening 11 through which the soil pipe or other pipe 12 may be introduced. The opening 11 is herein shown as having a transverse diameter substantially 55 equal to the distance between the sides 13

of the curb 3, and it has a longitudinal diameter which is considerably less than the distance between the end portions 5 and 6 of the curb so that there are portions 14 and 15 of the bottom 1 which are situated within the outline of the curb 3. These portions 14 and 15 constitute supports for the oakum or other packing 4 which is placed within the curb 3 around the pipe 12. They are also of a frangible nature so that they may 60 be readily broken or chipped thereby to enlarge the longitudinal dimension of the aperture 11. This frangible character of the bottom sections 14 and 15 may be secured in various ways. One way is to make these 65 portions relatively thin, as shown in the drawings, so that they may be readily broken or chipped by a hammer or other tool.

The roof flange is made in the first place 75 with the aperture 11 of sufficient size to easily receive the soil pipe 12 when the soil pipe extends through the bottom in a direction perpendicular thereto, as shown in Fig. 1, in which figure the device is illustrated 80 as applied to a flat roof. When used in this way the roof flange is placed on the roof as usual and the soil pipe or other pipe is inserted through the aperture 11. The space between the pipe and the wall 3 is then 85 packed with oakum or other suitable packing 4, and if desired hot lead 16 may be poured on top of the oakum to make a tight joint.

If the roof flange is to be used on a roof 90 having a relatively steep pitch, as shown in Fig. 3, it will be necessary to have the aperture 11 enlarged somewhat in its longitudinal dimension to accommodate the pipe 12. This may be readily done by breaking away 95 the edge of one or both of the bottom sections 14 and 15. The bottom section 15 is shown as having the greatest extent and the aperture 11 will preferably be enlarged by breaking away the edge 17 of the bottom 100 section 15 in order to provide an aperture of sufficient size to receive the pipe 12. When the roof flange is used on a steep pitched roof, as shown in Fig. 3, it will be necessary to break away the edge 17 of the bottom portion 15 until the aperture is enlarged about to the dotted line 18, Fig. 4. After the roof flange has been placed on the roof, as shown in Fig. 3, the space between the pipe and curb 3 is packed with oakum 105 110

or other packing in usual manner and the packing may be sealed by the application of melted lead to the top of the packing if desired.

The device is equally applicable to a roof having a less pitch, as shown in Fig. 2, it only being necessary to break away a less portion of one or both bottom sections 14, 15 to accommodate the pipe. In every instance, the bottom sections 14, 15 constitute supports for the packing and because the packing rests directly on the bottom it is not necessary to make the curb 3 of very great vertical dimension. The device is, therefore, a compact one which requires a relatively small amount of metal in its manufacture, a fact which reduces its cost.

I claim:

A roof flange having a bottom provided throughout its extent with a flat face to rest

on the roof and also having a relatively low oval-shaped wall or curb rising from the bottom a slight distance from its peripheral edge whereby said edge of the bottom forms a flashing-receiving flange on the exterior 25 of the wall, the end portions of said wall or curb being inclined relative to the bottom, and said bottom extending inwardly from the wall or curb and having a pipe-receiving aperture therein, the portion of 30 the bottom situated within the outline of the wall or curb constituting a support for the packing and being frangible so that it can be readily broken to enlarge the longitudinal dimension of said aperture whereby the 35 device may be used on either a flat roof or a pitched roof.

In testimony whereof, I have signed my name to this specification.

EDWARD F. DONNELLY.
